TROPHY

Paul F. Pisani, Chicago, Ill.

Application September 1, 1954, Serial No. 32,126

Term of patent 14 years

(Cl. D29—23)

Fig. 1.

Fig. 2.

Fig. 1 is a front perspective view of a trophy, showing my new design; and

Fig. 2 is a rear perspective view thereof.

The dominant features of my design reside in those portions shown in full lines.

A characteristic feature of my design resides in the offset relationship between the supporting base and the supported position of the figure relative thereto.

I claim:

The ornamental design for a trophy, substantially as shown and described.
